United States Patent Office.

HENRY STRICKLER, OF BOROUGH OF CARLISLE, PENNSYLVANIA.

Letters Patent No. 76,954, dated April 21, 1868.

IMPROVED HAY-HOISTING DRUM AND GRAIN-FORK.

The Schedule referred to in these Letters Patent and making part of the same.

TO ALL WHOM IT MAY CONCERN:

Be it known that I, HENRY STRICKLER, of the borough of Carlisle, county of Cumberland, and State of Pennsylvania, have invented a new and improved Hay-Hoisting Drum and Grain-Fork; and I do hereby declare that the following is a full, clear, and exact description thereof, which will enable those skilled in the art to make and use the same, reference being had to the accompanying drawing, which is a full and exact perspective view of the whole invention, and forms a part of this specification.

In the drawing, $a a' a'' a'''$ represents the front frame of a barn, and $b b' b'' b'''$ the side frame of the same. In the frame $a a' a'' a'''$ I erect vertically the conical shaft $c c'$, in the upper end of which is a stationary metallic spindle, which is to be inserted in the upper part of the frame, and in the lower end of the shaft is a box, x , in which is a movable pin, x' , prevented from sliding out by a shoulder or head on the upper end of it. The full length of this pin can be pushed into the shaft, when, the end of the shaft being placed over the hole in the lower frame, the pin drops down and fastens the shaft. On the shaft $c c'$, I place a movable drum, g , around which winds the rope ordinarily used in hoisting hay. Between this drum g and the shaft $c c'$, in a groove or gutter cut in the said shaft, is inserted the ratchet $f f'$, which, when drawn up, prevents the drum from revolving. This ratchet is operated from below by the lever e , and from above by the combination of the arm h , the rope w' , and the pulley w .

I further place upon the upper outer edge of the drum g , the bevelled cog-wheel m , which gears with the bevelled cog-wheel n , which can be shifted on its shaft o , whereby it is connected with the spur-wheel p , which gears with the spur-wheel q at the side of the barn-floor. On the rim of the spur-cog wheel q is fastened by a bolt and screw one end of the arm r , the other end of which is fastened in a similar way to the one end of the arm s , the other end of which is fastened by a bolt and burr to the metal extension t , which is fastened to a post at or near the middle of the side of the barn-floor. At any point in the upper side of the arm s , between its fastenings with the other arm r and the extension t , is inserted at right angles the fork u , the handle of which is of a length in proportion to the size of the barn. On the upper face of the side frame $b b' b'' b'''$ I erect the inclined plane v .

In unloading hay, the bevelled cog-wheel n is unshifted by moving it on its shaft o toward p . The horse is attached to the arm d , and walks continuously around. The rope ordinarily used is attached to the ordinary hook or fork, and winds around the drum g as the forkful of hay is going up, and when it is up and dropped, the drum is unshifted, either by the person working the hook or fork on the wagon, by the rope w' and the pulley w , and arm h , hitherto mentioned, or from the floor by the lever e .

In unloading grain, the bevelled cog-wheel n is shifted into gear with the bevelled cog-wheel m , and the motive-power applied to the arm d , as in unloading hay. The load of grain is then drawn near the side of the floor, and a person from the wagon pitches the sheaves on the fork u , which carries them to the inclined plane v , whence they slide into the mow.

I secured by Letters Patent, bearing date the 11th day of February, A. D. 1868, the shaft c , the drum g , the lower part of the shifting-ratchet $f f'$, the lever e , and the arm d .

What I claim now, and desire to secure by Letters Patent, is—

1. The extension f of the lower ratchet $f f'$, operating with the arm h and the pulley w , and the rope w' , for the purpose of enabling the person working the hook or fork on the loaded wagon therefrom to unshift the drum.
2. The bevelled cog-wheel m , fastened on the upper outer face of the drum g , the bevelled cog-wheel n , the arm o , the spur-cog wheel p , the spur-cog wheel q , the arm r , the arm s , the fork u , and the inclined plane v , all combined and operating in the manner and for the purpose herein set forth.

HENRY STRICKLER.
